UNITED STATES PATENT OFFICE.

EDMUND NOLAN, OF DETROIT, MICHIGAN, ASSIGNOR TO GEORGE W. BOWEN, OF AUBURN, NEW YORK.

GREASE-CUP CAP.

1,210,352.

Specification of Letters Patent. Patented Dec. 26, 1916.

Application filed October 27, 1915. Serial No. 58,194.

To all whom it may concern:

Be it known that I, EDMUND NOLAN, a citizen of the United States, and a resident of Detroit, in the county of Wayne and 5 State of Michigan, have invented a certain new and useful Grease-Cup Cap, of which the following is a specification.

This invention relates to grease cups and has for its object a particularly simple, efficient, and durable construction by which a 10 member of the ratcheting mechanism of the cup is secured to the cap; and the invention consists in the novel features of construction hereinafter set forth and claimed.

15 In describing this invention, reference is had to the accompanying drawings, in which like characters designate corresponding parts in all the views.

Figure 1 is an elevation of this cap. Fig. 20 2 is a longitudinal sectional view on line 2—2, Fig. 1. Fig. 3 is an inner face view looking upwardly in Fig. 1. Figs. 4 and 5 are elevations of the rod which is one of the members of the ratcheting mechanism of the 25 cup.

This invention comprises, generally, a grease cup cap having a portion or member thereof formed with opposing or double walls, and a member having a portion inserted between said opposing walls, the walls being compressed upon said member, and the member being embedded in said walls by the compressing of the walls.

1 designates the cap of the grease cup, 35 the cap being here shown as formed of sheet metal and having a top which has a double walled wing 2 compressed therefrom, this wing extending diametrically across the top and the space or crevice between the walls 40 thereof opening into the interior of the cap. The cap is also formed with internal threads for turning on the base of the cup.

3 is a member forming part of the ratchet mechanism of the cup, this member being 45 here shown as a rod having a head 4 extending between the walls of the wing. The head 4 is flattened and widened with respect to the rest of the rod, so that two shoulders 5 are provided at the base of the head, which 50 shoulders engage the inner face of the top, and the head is usually roughened or knurled.

After the cap has been formed with a hollow walled wing, the head 4 of the rod is 55 inserted between the walls of the wing and

said walls compressed upon the knurled head thereof for securing the rod to the head. The rod is non-circular, or square and is designed to coact with a suitable spring device which engages the sides thereof, said device being secured at the base of the grease cup and engaging the square sides of the rods so as to resist rotation of the rod, as will be understood by those skilled in the art. 60

What I claim is:

1. A grease cup cap formed with a member located on the top thereof and having opposing walls, the space between which opens into the interior of the cap, and a rod 70 extending lengthwise of the interior of the cap and having a portion extending between the opposing walls of said member, the walls being compressed upon the rod, substantially as and for the purpose set forth. 75

2. A grease cup cap including a portion formed with a double wall and a member extending lengthwise of the interior of the cap and having means clamped between said double wall, substantially as and for the 80 purpose described.

3. A grease cup cap formed with a double walled wing on the top thereof, and a rod 85 extending lengthwise of the interior of the cap and having a portion extending between the walls of the wing, substantially as and for the purpose specified.

4. A grease cup cap formed with a double walled wing on the top thereof and a rod 90 extending lengthwise of the interior of the cap and having a portion extending between the walls of the wing, the walls of the wing being compressed onto the rod, substantially as and for the purpose set forth.

5. A grease cup cap having a double 95 walled wing on the top thereof, and a rod extending lengthwise of the interior of the cap and having a roughened head inserted between the walls of the wing, said walls being compressed upon said head, substantially as and for the purpose described. 100

6. A grease cup cap formed of sheet metal and formed with a top having a double walled wing extending crosswise thereof, and a rod extending lengthwise of the interior of the cap and having its upper portion extending between the walls of the wing, and the walls of the wing being compressed upon said portion of the rod, substantially as and for the purpose specified. 105

7. A grease cup cap formed with a double walled wing on the top thereof, and a rod extending lengthwise of the interior of the cap and having a head and shoulders at the 5 base of the head, the head extending between the walls of the double wall and the shoulders engaging the inner face of the top, the double wall being compressed onto said

head, substantially as and for the purpose set forth.

In testimony whereof, I have hereunto signed my name, at Detroit, in the county of Wayne, in the State of Michigan, this 23rd day of Sept., 1915.

10

EDMUND NOLAN.
